HEATER HOUSING FOR HAIR CURLERS

Arne Bybjerg Pedersen, 42-46 Skibbrogade,
Kalundborg, Denmark

Filed Jan. 3, 1966, Ser. No. 406

Claims priority, application Canada Dec. 2, 1965

Term of patent 14 years

(Cl. D86—10)

Fig. 1

Fig. 4

Fig. 2

FIG. 1 is a front elevational view of a heater housing for hair curlers showing my new design;

FIG. 2 is a top plan view thereof;

FIG. 3 is a side elevational view, the side opposite being a mirror image thereof;

FIG. 4 is a front elevational view of the design as it appears in open position;

FIG. 5 is a top plan view thereof; and

FIG. 6 is a cross sectional view thereof.

I claim:

The ornamental design for a heater housing for hair curlers, as shown.
